UNITED STATES PATENT OFFICE.

HENRY B. NICHOLS, OF PHILADELPHIA, PENNSYLVANIA.

GRINDING-MACHINE.

No. 856,721.

Specification of Letters Patent.

Patented June 11, 1907.

Application filed July 13, 1906. Serial No. 326,002.

To all whom it may concern:

Be it known that I, HENRY B. NICHOLS, a citizen of the United States, residing at Philadelphia, in the county of Philadelphia and State of Pennsylvania, have invented a certain new and useful Improvement in Grinding-Machines, of which the following is a specification, reference being had therein to the accompanying drawing.

10 My invention relates to metal working machines, and particularly to those employed for grinding or surfacing curved or irregular forms.

15 My present invention is in the nature of an improvement on those which I have described and claimed in my Patents Nos. 807,193 and 807,194, granted December 12, 1905.

20 In my said patented machines I have made use of the principle of a moving tool and fixed work holder, that is the tool determining the shape of the cut and its extent, while the work holder or carrier merely determines the feed. The specific purpose of my patented machine is the grinding of the pins of 25 railway switch tongues, which become worn into irregular shapes and have to be restored to roundness. Since these pins are forged directly on the switch tongues, they cannot be removed for grinding, hence I arrange my 30 work holder to clamp the switch tongues with the pins projecting, and I then revolve my cutting tool while at the same time I rotate it upon its own axis. The revolving motion carries the tool around the pin, and the rotation secures the cut.

35 My object in the present case is to effect a special feed or reversal of motion of my cutting tool, whereby I may cut or grind a portion only of a surface.

40 The invention is applicable to a great many uses, but I will illustrate these by taking a single example.

45 The switch tongues to which I have referred are of considerable length, each having a rounded butt, which is set on the pivot-plate, and a long taper body terminating in a point. The pin or pivot is of course at the butt end, and not only this pin, but also the butt end of the tongue frequently requires 50 grinding. This, however, cannot be accomplished by a revolving tool, for the obvious reason that the rounded end is only semi-circular. I therefore desire in the present case to be able to feed my cutting tool through 55 any arc of a circle or other curved figure, and then reverse the motion. To grind the

switch tongue butt the arc of motion would extend through an angular distance of 180 degrees before reversal.

In attaining my object, I make use of the same general type of machine as that shown in my patents aforesaid, but I apply to this machine an additional feed or controlling mechanism which I shall presently describe in detail and which operates as follows: The work being fixed, and the tool shaft and swing plate adjusted, so that the required swing is obtained, the drive of the swing plate is taken up by one of a pair of loose pulleys carried on the swing plate spindle. These pulleys are oppositely belted to the feed gear of the machine, this part of the mechanism, as well as the ratio of motion, being immaterial to my present invention so long as the proper speed of travel is given the tool. The pulleys are alternately thrown in and out of engagement with the swing plate spindle by means of an intermediate double clutch, controlled by a system of levers which themselves are governed by a slide movement controlled by a fixed stud on the swing plate. By adjusting the slide members with regard to this stud, the latter may be caused to throw the clutch one way and the other at any desired point in the rotation of the swing plate, thereby instantly reversing the motion thereof. By setting the slide fingers sufficiently wide to escape the stud entirely, the machine may be caused to work steadily with complete rotation of the tool, and from this adjustments may be made that will permit a feed through any arc from 360 degrees down practically to zero, which would not be absolute zero, but merely the smallest arc through which the tool could be made to travel in the time required for reversal. Of course this extreme low limit would probably never be resorted to, but the possibility of being able to grind up within a fraction of a complete revolution, and then reverse, is very important.

There are many cases where projecting keys or studs or the like, in such pieces as the propeller shaft of a steamer, have prevented machine grinding. By my present invention it at once becomes possible to grind around the shaft to the projecting part in one direction, and then grind around the other way. In order to make the action of my clutch positive, I provide a locking weight for the system of levers, with lost motion in a link connection, so that when the

feed is reversed the weight is pushed just past center, and falls the rest of the way over, thereby positively actuating the clutch.

My invention is illustrated in the accompanying drawing, in which

Figure 1 is a side view of my grinding machine, with my present invention applied thereto. Fig. 2 is a similar view on a somewhat enlarged scale, of the feed mechanism and swing-plate of the machine. Fig. 3 is an end view of the parts shown in Fig. 2. Fig. 4 is a view on a section line $x-x$ of Fig. 1, looking in the direction of the arrow toward the swing-plate, and with the tool shaft removed.

Referring to the drawings and particularly to Fig. 1, 1 represents the bed of the machine which is or may be similar in construction to the bed of an engine-lathe and in this instance is supported on pedestals or standards 2. Bolted to the upper surface of the bed near one end thereof is the head-stock 3 in which is journaled the shaft 4 driven through the clutch 5 by the pulleys 6 and 7 loosely mounted on the shaft 4 and normally driven in opposite directions by belts or other suitable means. The inner end of the shaft carries the swing plate 8 to which is secured adjacent its periphery the semi-cylindrical socket piece 9 which forms a bearing for the ball shaped member 10 carried by the spindle yoke 11 in which is journaled the spindle 12 carrying at its outer end the dressing tool 13 which is driven by the belt 14 as described in my Patent No. 807,193. About midway of the bed of the machine is bolted the tool support 15 in which is mounted for rotary and oscillatory motion the yoke or bracket 11.

The work support 16 is mounted to slide upon the end of the bed plate opposite to that upon which the head-stock is located and carries means for supporting the switch tongues or other work to be operated upon. Depending from the center of the work support is an arm 17 to which is secured a rod 18 having upon it stops 19 and 20 adapted to operate the clutch 21 which reverses the feed mechanism, through the rod 22, as also described in my said Patent No. 807,193.

Secured to the bed plate and extending upwardly therefrom so that their upper ends will align transversely between the swing plate and head-stock, are a pair of arms 23 and 24, the latter being provided with a projecting portion 25, the function of which will be described hereinafter. Mounted to slide within apertures formed in the arms 23 and 24 is a horizontal cross rod 26 upon which are adjustably secured the fingers 27 and 28 having set screws 29 adapted to bear upon the under side of the rod 26 to secure the fingers in adjusted position. These fingers are provided at their upper ends with extensions 30 which are projected toward each other.

The operating stud 31 is adjustably secured to the swing plate 8 upon the opposite end from that holding the semi-cylindrical socket 9, and this stud is made to engage the adjusting fingers 27 and 28 alternately by mechanism which will be hereinafter described. Journaled in the extension 25 of the arm 24 is a shaft 32 upon which is secured a lever 33 having a graduated weight 34 at its upper end and approximately midway of its length is provided with a closed slot 35 which is engaged by a bolt 36 carried by the sliding rod 26. The shaft 32, which is journaled in the extension 25 of the arm 24, extends along the bed plate for some little distance and at one end thereof is provided with an arm 37 to which is secured a link 38 connecting the arm 37 and one end of an arm 39 on a bell crank lever formed by securing another arm 40 upon a transverse shaft 41 journaled in suitable uprights 42 carried by the bed plate. The arm 40 extends up toward the live shaft 4 and is forked at 43 to engage an annular depression 44 in the clutch 5.

Keyed to the shaft 4 is a sprocket pinion 45 conveying motion by the sprocket chain 46 to a larger sprocket wheel 47 carried by a short shaft 48 journaled in a Y-frame 49 secured in any suitable manner to the bed plate 1. This pinion 47 through its shaft 48 conveys motion to a smaller pinion 50 which in turn conveys motion to two sprocket-wheels 51 and 52, the former of which is journaled upon a stub shaft 53 and the latter of which is carried loosely upon the feed shaft 54, which extends to the opposite ends of the bed plate, where it has a worm gear connection with the tail stock or work support 16. Upon the shaft 53 and upon the shaft 54 are mounted gears 55 and 56, the former of which 55 is connected directly with the sprocket wheel 51 and meshes with the latter 56 this being loosely journaled upon the shaft 54 and receiving its motion either through the clutch 21 or through the gear wheel 55. Although this description of the reversing feed mechanism has been formerly given in my Patent 807,193, I describe it here so that it may be clearly understood that the machine is in every respect automatic and I will further say that the clutch 57 is operated by a forked lever 58 pivotally connected to a supporting arm 59 and operated by the rod 22. I have not shown mechanism for working the rod 22 as the same is shown and described in my patent before mentioned, but I may state that by adjusting the stops 19 and 20 upon the rod 18 and providing a depending arm or the rod 22 which will lie in the path of these stops, this is easily accomplished.

The operation of my device is as follows:— A tongue 60 is clamped to the work support by suitable clamps 61 and 62 with the pin 63 projecting in a horizontal direction toward

the tool support and head stock. The dressing tool is now adjusted through its hand-wheel 64 to bring it into engagement with the periphery of the pin 63. The shaft 4 is started to revolving by means of a belt shifter or the like, not shown herein, and according to the position of the clutch 5 one of the pulleys, 6 or 7, as the case may be, is started rotating. This being in engagement 10 with the clutch, which is keyed to the shaft 4, the shaft 4, also starts to rotate carrying with it the swing plate 8 and the spindle yoke 11, thereby revolving the dressing tool 13 around the pin 63. While this orbital or 15 planetary motion is being effected, the dressing tool is given a rotary motion through the spindle 12 by the belt 14. During this operation the fingers 27 and 28 mounted upon the rod 26 are so adjusted that the stud 31 20 does not come in engagement therewith during the rotation of the swing plate, allowing a complete rotation of the said swing plate and the dressing tool.

If it is desired to grind only one portion of 25 the pin 63, or for example the butt of the switch tongue which is rounded at that end and extends straight up so as to prevent the complete rotation of the dressing tool, the operation is somewhat changed and the tool 30 is given an oscillatory motion as follows: The fingers 27 and 28 are adjusted upon the rod 26 so as to give the desired throw to the swing plate upon each reversal. We may assume that the clutch is in engagement with the 35 pulley 6 and that the pulley is being driven in a left-hand direction while the pulley 7 is revolving idly upon the shaft 4 in a right-hand direction. When a part of the revolution of the swing plate is completed, the stud 40 31 engages the arm 28 and throws the rod 26 a predetermined distance which is sufficient to push the arm 33 and its weight 34 past the center or vertical line through the pivot point of the rod. The arm then drops further through force of gravity and for a distance governed by the length of its slot 35 performs no function whatever. When, however, the end of the slot is reached, the 45 rod 26 is snapped quickly over to the limit 50 of its movement and the shaft 32 is thus revolved, carrying with it the arm 27 and raising the arm 39 through the link 38 thereby operating the shaft 41 to reverse the clutch 5 through the forked arm 40. This operation 55 changes the rotation of the shaft from left to right and thereby reverses the direction of movement of the dressing tool the rotation of which is continued in the same direction. The next reversal is, of course, similar to that 60 thus described except that instead of the stud engaging the arm 28, it engages the arm 27 and throws the weighted arm 33 in the opposite direction.

The reversal of the shaft may, of course, 65 reverse the rotation of the pinion 45 and

thereby reverse the feed action of the shaft 54. If desired, however, to continue the same direction of feed, the stops 19 and 20 are so adjusted that they will reverse the action of the clutch 21 and thereby continue 70 the feed in the same direction although the shaft 4 is being operated in a reverse direction.

It will be understood that the mechanism thus specifically described may be varied by 75 skilled mechanics in various ways without departing from the spirit of my invention. The essential feature of the invention, and one which I believe to be original with me, is the reversal of the feed of the dressing tool in 80 less than a complete revolution of the shaft. Subsidiary features of the invention are the position of the weighted rod to insure the complete and positive operation of the reversing clutch, sufficient energy being stored 85 up in this weight and rod by permitting lost motion through the slot and connection. This also serves to maintain the clutch positively set in either direction after being thrown. 90

With this invention I have found it practicable to grind any fraction of a curved surface from one degree to three hundred and sixty degrees of rotation, and so far as I am aware I am the first person who has been 95 able to accomplish this important result. The practice of the invention is extensible to include many other things besides switch tongues, for example, the end of crank arms, and the curved butts of any straight sided 100 mechanical pieces, also such curved surfaces as the portions of propeller shafts or engine shafts generally which are included between projecting pins or keys or the like. None of these can be ground or in fact properly 105 dressed with any rotating tool, nor with a fixed tool cutting through rotation of the work, for the reason that there are obstructions. With my invention, however, it is only necessary to set the reversing fingers in 110 order to insure the complete and satisfactory grinding of any predetermined angular distance on the curved surface.

Among the changes which are possible, without altering the character of the invention, I may mention the modification of the work-holder or support so as to take objects extending parallel to the bed or machine; also the modification of the work-support and tool-holder to have the tool held by 120 what is herein considered the work-support, and the work-holder by what I have called the tool-support. Of course this latter change could only be effected where small parts are dealt with, but I mention it in order 125 to show the comprehensive scope of the field to which my present invention is applicable. I intend my claims appended hereto, to be given a broad and comprehensive scope in keeping with the broad and comprehensive 130

character of the field to which the invention is applicable.

Having thus described my invention what I claim and desire to secure by Letters Patent is:—

1. In a machine of the class described a supporting frame or bed, means for holding a piece of work in position thereon, a tool having a double drive, one drive for cutting and the other for surface feed over the work, together with means to limit and change the direction of the tool drive as desired, and means for automatically feeding the work holding means with respect to the tool.
2. In a machine of the class described a supporting frame or bed, means for holding a piece of work in position thereon, a tool having a double drive, one drive for cutting and the other for surface feed over the work, means to change the direction of the surface feed of the tool at will, together with means to feed the work holder.
3. In a machine of the class described a supporting frame or bed, means for holding a piece of work in position thereon, a tool having a double drive, one drive for cutting and the other for surface feed over the work, means to limit the extent of surface feed of said tool, means for feeding the work holder, and means for automatically limiting the same.
4. In a machine of the class described a supporting frame or bed, means for holding a piece of work in position thereon, a tool having a double drive, one drive for cutting and the other for surface feed over the work, means to direct the surface feed so as to effect a cut over a prescribed surface of the work only, means for automatically feeding the work holder, and means for effecting a reversal thereof.
5. In a machine of the class described a supporting frame or bed, means for holding a piece of work in position thereon, a tool having a double drive, one drive for cutting and the other for surface feed over the work, means for reversing the surface feed motion of the tool, means for feeding the work holder, and means automatically operating to reverse said feeding action at a predetermined time.
6. In a machine of the class described a supporting frame or bed, means for holding a piece of work in position thereon, a tool having a double drive, one drive for cutting and the other for surface feed over the work, means for automatically feeding the work holder with relation to the tool, a tool spindle carrying the tool and movable to effect the cutting drive, a feed spindle with connections to the tool spindle, whereby the latter is moved to effect the surface feed, together with means for limiting the motion of said feed spindle.
7. In a machine of the class described a supporting frame or bed, means for holding a

piece of work in position thereon, a tool having a double drive, one drive for cutting and the other for surface feed over the work, means for automatically feeding the work holder with relation to the tool, a tool spindle carrying the tool and movable to effect the cutting drive, a feed spindle with connections to the tool spindle, whereby the latter is moved to effect the surface feed, together with reversing mechanism controlled by the tool spindle in its motion for effecting a change in said motion.

8. In a machine of the class described a supporting frame or bed, means for holding a piece of work in position thereon, a tool having a double drive, one drive for cutting and the other for surface feed over the work, means for automatically feeding the work holder with relation to the tool, a tool spindle carrying the tool and movable to effect the cutting drive, a feed spindle with connections to the tool spindle, whereby the latter is moved to effect the surface feed, together with reversing mechanism controlled by the tool spindle in its motion for effecting a change in said motion.

9. In a machine of the class described a supporting frame or bed, means for holding a piece of work in position thereon, a tool having a double drive, one drive for cutting and the other for surface feed over the work, means for automatically feeding the work holder with relation to the tool, a tool spindle carrying the tool and movable to effect the cutting drive, a feed spindle with connections to the tool spindle, whereby the latter is moved to effect the surface feed, together with reversing mechanism controlled by the tool spindle in its motion for effecting a change in said motion.

10. In a machine of the class described a supporting frame or bed, means for holding a piece of work in position thereon, a tool having a double drive, one drive for cutting and the other for surface feed over the work, means for automatically feeding the work holder with relation to the tool, a tool spindle carrying the tool and movable to effect the cutting drive, a feed spindle with connections to the tool spindle, whereby the latter is moved to effect the surface feed, together with oppositely driven motor means for said feed spindle, a reversing lever for throwing in one or the other of the motor means, and automatic controlling means for said reversing lever.

11. In a machine of the class described a supporting frame or bed, means for holding a piece of work in position thereon, a tool having a double drive, one drive for cutting and the other for surface feed over the work, means for automatically feeding the work holder with relation to the tool, a tool spindle carrying the tool and movable to effect the cutting drive, a feed spindle with connections to the tool spindle, whereby the latter is moved to effect the surface feed, together with oppositely driven pulleys on said feed spindle, a clutch adapted to connect either one of said pulleys to the spindle, and means actuated by the spindle in its motion to control said clutch.

- carrying the tool and movable to effect the cutting drive, a feed spindle with connections to the tool spindle, whereby the latter is moved to effect the surface feed, together with reversing mechanism for said spindle and a double controlling mechanism therefor for producing a continuous back and forth motion of the feed spindle.
12. In a machine of the class described a supporting frame or bed, means for holding a piece of work in position thereon, a tool having a double drive, one drive for cutting and the other for surface feed over the work, means for automatically feeding the work holder with relation to the tool, a tool spindle carrying the tool and movable to effect the cutting drive, a feed spindle with connections to the tool spindle, whereby the latter is moved to effect the surface feed, together with reversing drive pulleys for said spindle, a clutch for connecting one or the other thereto, a lever controlling said clutch, a spindle controlling said lever, a slide bar adapted to move said spindle, adjustable fingers on said bar, and a reversing stud connected with the feed spindle, to act upon said fingers and thereby produce alternate reversals of motion of the spindle.
13. In a machine of the class described a supporting frame or bed, means for holding a piece of work in position thereon, a tool having a double drive, one drive for cutting and the other for surface feed over the work, means for automatically feeding the work holder with relation to the tool, a tool spindle carrying the tool and movable to effect the cutting drive, a feed spindle with connections to the tool spindle, whereby the latter is moved to effect the surface feed, together with reversible driving gear for the feed spindle, a link motion therefor controlled by the spindle in its movement, and a locking device initially moved by the spindle, and thereafter acting automatically to insure a complete and positive reversal.
14. In a machine of the class described a supporting frame or bed, means for holding a piece of work in position thereon, a tool having a double drive, one drive for cutting and the other for surface feed over the work, a tool spindle carrying the tool and movable to effect the cutting drive, a feed spindle with connections to the tool spindle, whereby the latter is moved to effect the surface feed, together with reversing gear for the feed spindle, and a weighted lever connected thereto with lost motion, and means for initially moving said lever in the act of reversing to a point where it will continue to act under the influence of gravity, to force a positive reversal.
15. In a machine of the class described a supporting frame or bed, means for holding a piece of work in position thereon, a tool hav-
- ing a double drive, one drive for cutting and the other for surface feed over the work, a tool spindle carrying the tool and movable to effect the cutting drive, a feed spindle with connections to the tool spindle, whereby the latter is moved to effect the surface feed, together with oppositely running drive pulleys for the feed spindle, a clutch for connecting either one of said pulleys at will, a lever controlling said clutch, a link spindle controlling said lever, a slide bar controlling said link spindle, and a weighted lever rigidly secured to said spindle and having a lost motion connection with the slide bar, whereby it may be thrown past center by said slide bar, and thereafter will act under the influence of gravity to effect a complete and positive motion of the link and spindle clutch mechanism.
16. In a machine of the class described a supporting frame or bed, means for holding a piece of work in position thereon, a tool having a double drive, one drive for cutting and the other for surface feed over the work, a tool spindle carrying the tool and movable to effect the cutting drive, a feed spindle with connections to the tool spindle, whereby the latter is moved to effect the surface feed, together with a pair of oppositely running drive pulleys for the feed spindle, an intermediate clutch thereon, a bell-crank lever pivotally carried on the bed of the machine, a reversing spindle in bearings on said bed, a link connection from said reversing spindle to the bell-crank lever, a weighted operating lever rigidly secured at its lower end to said reversing spindle, a slide bar carrying adjustable fingers and adapted to be moved back and forth by a stud connected to the feed spindle and a lost motion connection between the slide bar and the weighted lever, whereby movement of the bar in either direction will force the lever past center and then permit a free and uninterrupted continuance of its motion under the influence of gravity, to produce positive action of the clutch.
17. In a machine of the class described, the combination of a supporting frame or bed, of a work holder slidably mounted thereon, means for feeding said work holder, a tool having a double drive, one drive for cutting and the other for surface feed over the work, means for changing the direction of surface feed of said tool over the work, and means for locking said changing means in changed position.
18. In a machine of the class described, the combination of a supporting frame or bed, of a work holder slidably mounted thereon, means for feeding said work holder, a tool having a double drive, one drive for cutting and the other for surface feed over the work, means for changing the direction of surface feed of said tool over the work means

for locking said changing means in changed position, and means for reversing the feed of said work holder.

19. In a machine of the class described, a supporting frame or bed, means for holding a piece of work in position thereon, a tool having a double drive, one drive for cutting and the other for curved surface feed over the work, together with means to limit and change the direction of the surface drive as desired.

20. In a machine of the class described, a supporting frame or bed, means for holding a piece of work in position thereon, a tool having a double drive, one drive for cutting and the other for curved surface feed over the work, together with means to direct said

15 curved surface feed so as to effect a cut over a predetermined surface of the work only.

21. In a machine of the class described, a supporting frame or bed, means for holding a piece of work in position thereon, a tool having a double drive, one drive for cutting and the other for curved surface feed over the work, a tool spindle carrying the tool and movable to effect the cutting drive, a feed spindle with connections to the tool spindle whereby the latter is moved in a rotary direction to effect the surface feed, together with means for limiting and changing the direction of motion of said feed spindle.

In testimony whereof I have affixed my signature in presence of two witnesses.

HENRY B. NICHOLS.
